UNITED STATES PATENT OFFICE.

JOHN G. KOEGLE, OF TOLEDO, OHIO, ASSIGNOR OF ONE-HALF TO HUGO BOELTER, OF TOLEDO, OHIO.

CASTING MACHINE.

Application filed June 17, 1926. Serial No. 116,603.

My invention has for its object to provide an efficient casting machine for casting metals of different forms such as, iron, brass, aluminum, etc., in a mold which is so constructed that the castings may be rapidly formed and removed and wherein relatively soft iron castings, when iron castings are formed, may be produced having machinable parts or faces.

10 The invention may be contained in structures of different forms and to illustrate a practical application of the invention I have selected a structure containing the invention as an illustration of such structures 15 and shall describe it hereinafter. The structure selected is particularly applicable to casting valve heads for internal combustion engines and welding the heads to the stems in the casting operation. The invention also 20 provides a stem structure whereby an efficient weld may be made. A structure, selected as an example of casting machines containing my invention, is shown in the accompanying drawings.

25 Figure 1 is a side view of the casting machine. Fig. 2 is a view of a vertical section through the machine. Fig. 3 is a view of a section of a part of the casting head of the machine somewhat larger than the proportionate sizes in Figs. 1 and 2, to show 30 more accurately the details of construction of the head of the casting machine. Fig. 4 is a view of the mold opened, a part of the mold being shown broken away and parts 35 removed, to show more in detail the structure of the mold. Fig. 5 illustrates a side view of a part of the mold. Fig. 6 illustrates the manner in which the surplus metal that passes through the gates of the mold 40 is severed from the casting. Fig. 7 illustrates the drawn casting. Fig. 8 illustrates a perspective view of the end of the stem that is welded to the valve head. Fig. 9 is a view of a section showing the withdrawal 45 of the portion that forms the lower side of a matrix of the mold. Fig. 10 illustrates the position of the end of the stem relative to a matrix when in position to be 50 welded to the head in the casting operation.

55 The casting machine may be provided with a suitable base 1. The casting machine head or mold 2 is supported on the base 1 by suitable uprights or pedestals such as the rods 3. The mold 2 comprises two parts 4 and 5 that are hingedly connected by

means of the pintle or rod 6. The part 4 is connected to the rods 3 while the part 5 is swung relative to the part 4 by means of a suitable handle, such as, a handle 7, to open and close the mold.

60 The parts 4 and 5 have registering recesses 8 and 9 that, when the parts are closed, form the matrices of the mold. The part 5 has the sprue hole 10 having a conical surface. The gate-ways formed by the recesses 11 connect a sprue hole 10 with the recesses 9 formed in the part 5. A cone 12 is secured to the part 4 by means of a bolt 13. The apex of the cone is located substantially in the axis of the sprue hole 10. The cone 12 65 closes one side of each of the recesses 11 which consequently form the gateways between the sprue hole and the cavities of the mold when the parts 4 and 5 are closed and so that when metal is poured into the sprue 70 hole 10 it will flow down the surface of the cone 12 through the gates and into the matrices of the mold.

75 Since the machine is for forming valves for internal combustion engines, means is 80 provided for properly locating the ends of the rods that form the stems of the valves within the matrices of the molds so that they may be welded to the valve heads in the casting of the heads. The machine is provided 85 with a plate 16 that is adjustably supported with reference to the part 4 of the mold for supporting the stems in position while the valve heads are cast. The plate 16 may be 90 threaded on to the rod 17 that is longitudinally movable in a boss 18 that may be cast integral with the base 1 of the machine. The rod 17 is provided with a rack 19 and a sector 20 may be pivotally connected to the base 1, such as in the boss 18, for raising and 95 lowering the rod 17 by the operation of the sector 20. A lever 21 may be connected to the sector 20 for operating the disc. Thus the plate 16 may be adjustably located with 100 reference to the mold and may be raised and lowered as may be desired in order to manipulate parts of the machine.

105 Prior to the pouring of the metal the rods 24 are inserted through suitable openings formed in the part 4 until their lower ends rest upon the plate 16. If desired the plate 16 may be provided with a plurality of elastic cups 25 for elastically engaging the lower ends of the rods. The plate 16 is so located 110 that when in its uppermost position as de-

terminated by the rack 19 and the sector 20 the upper ends of the rods 24 will be located centrally with respect to the matrices of the mold. When, therefore, the metal is poured 5 it will surround the upper ends of the rods.

In order that the ends of the rods may be brought up to a welding heat, so that when the valve heads are cooled, the heads and the rods will be welded into an integral 10 structure, means is provided for allowing a certain amount of the metal to flow into and through the matrices of the mold to convey to the rods the required welding heat. The part 5 is thus provided with cavities 26 that 15 communicate with the matrices of the molds and which will be filled to a more or less extent by the surplus metal that is used for heating the rods. The cavities 26 also provide for the removal of the first metal that enters the 20 matrices which not only heats the rod but also heats the surface of the matrices and leaves within the matrices, possibly, a better metal than would otherwise occur where castings are formed of iron or brass. The 25 immediate preheating of the surfaces of the matrices by the molten metal that is directed into the matrices and then removed by entrance into the cavities, produces relatively soft castings having surfaces that may be 30 machined.

The portion of the metal that enters the cavities 26 may, while the metal is still soft, be severed from the metal that forms the valve heads. In order that this may be done 35 the part 5 is provided with a channel 27 in which a ring 28 is located and the cavities 26 are formed in the ring 28. The part 5 is also provided with a plurality of holes 29 that communicate with the matrices that are 40 formed by the recesses 8 and 9. The ring 28 is so located in the part 5 that the lower ends of the cavities 26 may register with the openings 29 and so that the cavities may receive the metal from the matrices of the 45 mold. The part 5 is also provided with a slot 30 that extends through its side to the channel 27 and a rod 31 is secured in the ring 28 and extends through the slot 30. While the metal in the cavities 26 is soft, 50 the rod 31 may be moved along the slot 30 so as to cut off the connection between the metal in the cavities 26 and the metal in the matrices of the mold. The cavities 26 have inverted cone surfaces so that when the part 55 5 is turned over by a pivotal movement on the rod 6 the metal in the cavities 26 are dropped out.

In order to produce a fine grain casting the matrices of the mold may be provided 60 with suitable linings of refractory material, if desired, or suitable chills may be located where it is desired to produce chill castings or chilled portions of the castings. In the machine selected for purposes of illustration 65 for casting valves it is found desirable to

locate a ring formed of non-metallic refractory material such as a graphite composition about each matrix to form a non-chilling part of the mold. The rings are so formed and located such that the portions of 75 the valves 32 that come in contact with their seats may be formed of a soft fine grain metal that may be machined or ground to fit the seats that they cooperate with when they are placed in position in the engines 77 in connection with which they are to be used. The part 4 is thus recessed so as to receive the graphite rings 34 which have bevelled edges 35 that conform to the bevelled portions of the valves. 81

In order that the valves may be readily drawn from the mold, on the completion of the casting they are preferably loosened. This may be done when the rod 17 is lowered by the operation of the sector 20. The upper 85 end of the rod 17 is connected to a plate 36 through which the rods 3 extend. The rods 3 operate to guide the plate 36 then moved by the rod 17. If desired springs 37 may be located on the rods 3 to counterbalance 90 the weight of the plate 36 and the rods 17 and to normally force the plate 36 upwards. The plate 36 is provided with a plurality of sleeves 38 in which the rods 24, that form the stems of the valves, are located. The 95 upper ends of the sleeves 38 are flared outward and form the lower surfaces of the matrices of the mold. The sleeves 38 may extend through the plate 36 and be secured in position by means of nuts 39. The upper 100 end edges of the sleeves 38 are elastically held by means of the springs 43 into contact with a conical surface 40 formed on the graphitic rings 34. The springs 43 thus operate to close this portion of each matrix of the mold. 105

In order to reduce the chilling action of the rods 24 they are inserted in the sleeves 38. The sleeves 38 may be heated by electric resistance wires 43 that are preferably located on sleeves of insulating material 44 110 that surround the sleeves 38. The resistance wires 43 will when connected to a source of supply of electric current maintain the sleeves 38 at a high temperature and will consequently raise the temperature of the rods 24 that form the stems of the valve to a high temperature and so that the metal that enters the matrices will not be cooled at an undesired rate. The resistance wires moreover operate to heat to a high temperature, 115 the portions of the mold that surround the matrices. This enables the production of soft castings in the molds while the spaces between the upper ends of the sleeves 38 and the graphitic rings 34 provides for the escape of gases that may be formed within the matrices of the mold or that may be created by or be exuded from the molten metal with the result that exceedingly fine and 120 substantially perfect castings are formed by 125 130

the machine. Preparatory to forming the castings in the machine, it is found preferable to heat the entire machine to a high temperature by a suitable heating means such as a blow torch, or, if desired, substantially the same results may be obtained by making a few castings and throwing them away, if imperfect, until the temperature of the mold is raised sufficiently high to produce the desired structural iron in the castings in the continued use of the machine. By making castings repeatedly and with reasonable rapidity it will maintain the mold at the proper high temperature, particularly, where the resistance wires 43 are used to aid in furnishing heat to the mold.

In order to perfect the weld of the rods with the valve heads 32 that is produced by the overflow of metal, that is, in order that the ends of the rods 24 may be readily brought to a welding heat by the use of a relatively small amount of additional metal, the ends of the rods are split into two or more tongues. Preferably, the laterally extending tongues 47 are formed about a central core or projection 48 that is located within the matrices of the mold. The subdivision of the ends of the rods into tongues increases the area of contact with the molten metal proportionate to the quantity of iron in the ends of the rods which quickly raises the temperature to the necessary fluxing or welding point and moreover produces a more positive union between the parts. Furthermore, if the contraction rate of the head and rod should differ, the rod nevertheless will remain interlocked in the head.

I claim:

1. In a casting machine, a mold having two parts, one of the parts having a non-inverted cone shaped sprue hole and recesses forming the gateways and a side of each of the matrices of the mold, the other part for closing one side of each of the recesses that

form the gateways and having recesses that with the other of the said recesses of the first named part form the matrices of the mold.

2. In a casting machine, a mold having two parts, one of the parts having a non-inverted cone shaped sprue hole and recesses forming the gateways and a side of each of the matrices of the mold, the other part for closing one side of each of the recesses that form the gateways and having recesses that with the other of the said recesses of the first named part form the matrices of the mold, a member slidably connected to one of the parts and having cavities communicating with the matrices.

3. In a casting machine, a mold having two parts, one of the parts having a non-inverted cone shaped sprue hole and recesses forming the gateways and a side of each of the matrices of the mold, the other part for closing one side of each of the recesses that form the gateways and having recesses that with the other of the said recesses of the first named part form the matrices of the mold, a ring slidably connected to one of the parts and having cavities communicating with the matrices.

4. In a casting machine, a mold having two parts, one of the parts having a non-inverted cone shaped sprue hole and recesses forming the gateways and a side of each of the matrices of the mold, the other part for closing one side of each of the recesses that form the gateways and having recesses that with the other of the said recesses of the first named part form the matrices of the mold, one of the parts having an annular slot and a ring slidably movable in the slot, the ring having cavities communicating with the matrices.

In testimony whereof I have hereunto signed my name to this specification.

JOHN G. KOEGLER.
